UNITED STATES PATENT OFFICE.

PAUL SCHNEIDER, HENRY TRENKAMP, AND BERNARD A. GEURINK, OF CLEVELAND, OHIO, ASSIGNORS TO THE SCHNEIDER & TRENKAMP COMPANY, OF SAME PLACE.

HYDROCARBON-BURNER.

SPECIFICATION forming part of Letters Patent No. 593,243, dated November 9, 1897.

Application filed March 11, 1896. Serial No. 582,720. (No model.)

To all whom it may concern:

Be it known that we, PAUL SCHNEIDER, HENRY TRENKAMP, and BERNARD A. GEURINK, citizens of the United States, and residents of Cleveland, county of Cuyahoga, and State of Ohio, have invented certain new and useful Improvements in Hydrocarbon-Burners, of which the following is a specification, the principle of the invention being herein explained and the best mode in which we have contemplated applying that principle, so as to distinguish it from other inventions.

The annexed drawings and the following description set forth in detail one mechanical form embodying the invention, such detail construction being but one of various mechanical forms in which the principle of the invention may be used.

In said annexed drawings, Figure I represents a side view of our improved hydrocarbon-burner; Fig. II, a vertical section of a portion of the bent supply-tube, the needle-valve, and drip-gage on the line II II in Fig. IV of the burner; Fig. III, a vertical section on the line III III in Fig. IV of the burner; Fig. IV, a top plan view of the burner; and Fig. V, a transverse section looking upward from the line V V in Fig. I and illustrating the drip-cup, the remainder of the burner being omitted.

The hydrocarbon fluid is supplied to an axial tube A of the burner through a suitable coupling A', connected to the hydrocarbon-reservoir or other source for the fluid. A tube a of smaller diameter than the axial tube extends downward against the upper side of the axial tube and communicates with the same at the upper end. Said small tube has a laterally-diverging lower portion a', which merges into a jet-nozzle a'', which is regulated by means of an ordinary needle-valve A'', having a suitable hand-wheel A''' or other means for rotating it. The jet-nozzle is furthermore provided with a downwardly-projecting drip-
lip a''. The jet-nozzle registers with the open end of a tube B, which is doubled upon itself. The open end of the tube is formed with an enlargement b, which widens outward and downward. The other end of the tube enters the burner proper, C. Said burner is annu-

lar, and the end of the doubled tube enters the annular burner upwardly at a tangent, so that mingled air and gases which pass through the doubled tube may enter the annular burner and receive a whirling helical upward movement which will carry the air and gases to all points of the burner. 55

The top of the burner consists of an annular domed burner-plate C', the upper side of which is formed with radiating kerfs c, through which the mingled air and gases escape, and the central portion of said plate extends downward to form a flange c', which surrounds the upper portion of the axial tube and has horizontal kerfs c'', through which flame-jets may issue and heat the upper portion of the axial vapor-supply pipe A. A trough-shaped fluid-gage D is supported from the widened end of the doubled tube beneath the jet-nozzle and its lip, so that fluid may drip from the jet-nozzle down into said gage-cup. Said gage-cup has a downwardly-projecting nozzle d, which is controlled by a valve d', consisting of a metal rod sliding in a cylindrical bore d'', which intersects the nozzle. A forked block d''' is secured upon the drip-valve rod by means of a set-screw d'', and said block has a guide-lug d''' projecting from one of its arms, which guide-lug slides in a guide-opening d'' in the end of the drip-gage. A cam-disk D' is secured upon the needle-valve rod by means of a set-screw d'' and has its periphery engaging between the arms of the forked block d''. The cam-disk is plane, with the exception of a short bulge d'', which diverges from the plane 80 of the disk. An annular air-space is formed around the fluid-supply tube by means of a perforated tube E and is closed at its upper end by an annular cap e. The lower end of the perforated tube is secured to an annular drip-cup F, which is secured to the axial fluid-supply tube by means of a set-screw f and is spaced from the tube by means of radial lugs f', so that the air may enter the annular space around the fluid-supply tube from 85 below. The drip-cup has a laterally-projecting extension f'', which extends under the drip-nozzle of the drip-gage. A perforated cylinder E' is secured to the edges of the annular drip-cup and extends upward. An im- 90

100

perforate casing E^2 is supported from the drip-cup and has its upper contracted end resting against the upper edge of the perforated cylinder E . The casing is supported with its lower edge a short distance above the upper edge of the drip-cup and surrounds the perforated cylinder, so as to form an annular air-space around said cylinder. An annular flame-space is thus formed above the drip-cup, and air may be supplied to both sides of said flame-space through the perforated tube and cylinder, the flame-space being thus supplied with air from within and from without.

15 When the burner is applied in a stove and suitably connected to a supply of gasoline or similar hydrocarbon fluid and it is desired to start the burner, the needle-valve is opened by rotating it upon its axis. This will bring 20 the plane portion of the cam-disk between the arms of the forked block upon the drip-valve, thereby pushing said drip-valve, so as to close the drip-nozzle, so that the fluid which is projected at the jet-nozzle into the 25 open end of the curved pipe may flow down the inclined enlargement in said pipe into the drip-gage and fill the same. When the drip-gage is filled, the needle-valve is again closed, causing the bulge upon the cam-disk to withdraw the drip-valve and open the drip-nozzle, allowing the fluid to flow into the lateral extension of the drip-cup and down into the latter. The fluid in the drip-cup may 30 now be ignited, and the flame will receive an air-supply from within and from without, so that it will burn with a hot and blue flame, heating the burner and the axial supply-pipe and vaporizing the fluid in said pipe. When the burner is sufficiently hot to vaporize the 35 fluid, the needle-valve is opened and the vaporized fluid will rush out at the jet-nozzle into the open end of the curved pipe, where it will mingle with atmospheric air drawn into the pipe by the jet of vapor and enter 40 the annular burner with a whirling motion, which will carry the mingled air and vapor 45 around the entire annular space in the burner.

The mingled air and vapor will escape 50 through the radial kerfs and will ignite from the drip-cup flame. The jets which issue from the horizontal kerfs in the annular flange of the burner-cap will keep the upper end of the supply-pipe heated, so that the fluid will be perfectly vaporized before it issues at the jet-nozzle. The drip-gage will admit of a sufficient quantity of fluid being supplied to the drip-cup to completely heat the burner before the needle-valve of the jet-nozzle is turned on 55 to supply vapor, and the cam-disk upon the 60 needle-valve stem will insure the closing of the drip-valve when the needle-valve is opened and the opening of the drip-valve when the needle-valve is closed, so that the exact amount of fluid may be drawn and supplied 65 to the drip-cup without danger of overflowing the latter.

A smaller amount of fluid will be required

for heating the burner in the present form of drip-cup and burner for the same than in the ordinary form of open drip-cup, as a full supply of atmospheric air is fed to both sides of the flame from the ignited fluid in the drip-cup through the perforated tube and cylinder, whereby an intensely hot flame is produced. Furthermore, the imperforate casting or mantle which surrounds the drip-cup burner protects the flame from the air and prevents it from being blown out by accidental draft striking it. The jets which strike the upper portion of the supply-pipe 80 will at all times insure perfect vaporization of the fluid irrespective of the temperature of the surrounding atmosphere. As the cam-disk is adjustable upon the needle-valve stem and the forked block is adjustable upon the drip-valve stem, both of said elements being adjustably secured by means of set-screws, the proper coöperation between the needle-valve and the drip-valve may at all times be insured, and any irregularity in their operation caused by wear or other causes may be taken up and readjusted.

The curved mixing-tube is formed in the shape of a segment of a helix. This peculiarity of construction enables us to obtain the length of tube required for properly mixing the vapor and air in less lateral area than would be possible by the use of the circular form of mixing-chamber. Further, the fact that the tube enters the burner in an upward direction has a most beneficial effect, as has been found by practical experience. By so entering the vapor escapes through the kerfs more easily, being assisted by its own inertia, thereby reducing the pressure of the vapor upon the liquid hydrocarbon in the reservoir, and hence requiring less heat to vaporize the said hydrocarbon, for the greater the pressure upon the liquid the greater the amount of heat required to vaporize it. Thus the burner does not require so much preliminary heating in order to start it, and consequently less oil may be used in the drip-cup.

Other modes of applying the principle of our invention may be employed for the mode herein explained. Change may therefore be made as regards the mechanism thus disclosed, provided the principles of construction set forth, respectively, in the following claims are employed.

We therefore particularly point out and distinctly claim as our invention—

1. In a hydrocarbon-burner, the combination of a drip-cup, a jet-nozzle, a drip-gage beneath said nozzle and formed with a nozzle delivering into said drip-cup, a valve for the jet-nozzle, a valve for the gage-cup nozzle, and mechanism connected to said valves and constructed to close the gage-nozzle valve when the jet-nozzle valve is opened and vice versa, substantially as set forth.

2. In a hydrocarbon-burner, the combination of a drip-cup, a jet-nozzle, a drip-gage provided with a drip-nozzle, a needle-valve for

the jet-nozzle, a sliding valve controlling the drip-nozzle, a forked block upon the stem of the drip-nozzle valve, and a cam-disk upon the needle-valve stem and formed with a cam-bulge, said cam-disk engaging the forked block, substantially as set forth.

5 In a hydrocarbon-burner, the combination of a drip-cup, a jet-nozzle, a drip-gage provided with a drip-nozzle, a needle-valve for the jet-nozzle, a sliding valve controlling the drip-nozzle, a forked block adjustably secured upon the drip-valve stem, and a cam-disk adjustably secured upon the needle-valve stem

and formed with a cam-bulge, said cam-disk engaging the forked block, substantially as 15 set forth.

In testimony that we claim the foregoing to be our invention we have hereunto set our hands this 9th day of March, A. D. 1896.
